IRONING BOARD COVER

Grange K. Pattison, Chicago, Ill., assignor to Textile Mills Company, Chicago, Ill., a corporation of Illinois

Application May 3, 1949, Serial No. 91,051

3 Claims. (Cl. 38—140)

1

This invention relates to ironing board covers and its primary object is the provision of a new and improved ironing board cover, whereby the top, or ironing surface, is of a predetermined kind, or type of material, such as asbestos, to which there is secured a relatively inexpensive material of cotton, preferably cut on the bias, the outer edges of the cotton material being bound with an elastic tape so that the cover may be easily applied to an ironing board and maintained on the board in a stretched position, so that there will be no wrinkles in the ironing surface.

Another important object of the invention resides in the provision of an ironing board cover which is provided with a top surface substantially equal in size and area to the top of an ironing board, there being a light-weight easily stretchable, inexpensive material, stitched about the boundary of the ironing surface of the cover so as to overhang the side edges of the board about its periphery elastic material in the form of a binding tape being secured to the free outer edges of the cotton material to permit easy application of the cover to the board.

Still a further object of the invention consists of the provision of an ironing board cover having an ironing surface of a predetermined material of a relatively expensive nature and a band of inexpensive material arranged peripherally about the top surface so as to permit a considerable reduction in cost and easy application of the cover to an ironing board without any bulky wrinkled edges or surfaces.

Other important objects and advantages will be apparent throughout the specification which follows. The accompanying drawing illustrates a certain selective embodiment of the invention and the views therein are as follows:

Fig. 1 is a detail perspective view of the improved ironing board cover, the same being shown arranged over an ironing board;

Fig. 2 is a detail sectional view through an ironing board, and showing the cover partly applied thereto;

Fig. 3 is a detail sectional view showing the cover arranged in final form over an ironing board, and

Fig. 4 is a detail sectional view showing the manner in which the asbestos top is connected to the cotton side walls and the manner in which the attached edges are secured by a binding tape.

The particular ironing board cover herein shown for the purpose of illustrating the invention, comprises a top or ironing surface 1 which

is preferably made of a material to withstand hard usage and to provide a smooth burn resisting ironing surface. The material from which the top or ironing surface 1 is made is preferably asbestos woven material which is relatively expensive, but which has certain qualities to provide a smooth ironing surface which is burn resisting and which has long wearing qualities. In view of the fact that the asbestos surface 1 is relatively thick, as well as expensive, it is desirable that the actual asbestos material used be no greater than the top surface of an ironing board 2 over which the material is placed. Furthermore, the thickness of the asbestos material is such that if it were extended over the peripheral edges of the ironing board and then tucked under the bottom of the board, the side edges would be relatively bulky, there probably would be considerable seams and wrinkles, and it would be difficult to maintain it in proper position due to the thickness and bulkiness of the asbestos material. Moreover, there is practically no stretch, if any, to the asbestos material and therefore, it would be difficult to apply it smoothly and evenly over the top of the ironing board so as to eliminate all wrinkles on the ironing surface.

The invention maintains all the advantages inherent in an asbestos ironing board top, but eliminates certain undesirable features which would be inherent were the entire cover made of the asbestos material.

A strip of relatively thin, inexpensive material, such as cotton 3, is sewed about the entire peripheral edge of the top end and then bound by a piece of binding material 4, such as cotton tape. The top 1 of asbestos material terminates in a free or raw edge 5. The attaching edge of the cotton side material 3 also terminates in a free raw edge as indicated by the numeral 6. The edges 5 and 6 are arranged in contacting overlapping relation as clearly shown in Fig. 4, and the binding tape 4 has its free edges 7 and 8 engaging the top surface of the asbestos material 1 and the lower surface of the cotton side edge 3 and then folded back upon itself as indicated at 9. Stitching 10 in the form of cotton thread or other suitable fastening means, passes through the two upper thicknesses of the tape, the free edge 5 of the asbestos material 1, the free edge 6 of the cotton side material 3, and the overlapped edges of the tape at the bottom, all as clearly shown in Fig. 4.

The cotton edging material 3 is relatively thin but strong, and it is cut on the bias so that there

will be a certain amount of vertical stretch as well as a certain amount of horizontal stretch. The cutting of the material 3 on the bias also eliminates any unraveling from occurring at the top and bottom free edges of the cotton material 3.

It is desirable that the ironing board cover be provided with means for maintaining the material in taut or stretched condition so as to eliminate any wrinkles from occurring in the ironing surface. It is desirable too, that means be provided to permit the ironing board cover to be easily applied and removed. Therefore, the lower edge of the cotton material has secured entirely thereabout, elastic material 11. This elastic material is in tape form and is folded over upon itself to provide a U-shape mouth 12 to receive the lower free edge 13 of the cotton side edging 3. This elastic material 11 is stitched along the line 14 and the stitching passes through the two plies of elastic material and the free edge 13 of the cotton material which is arranged in the mouth 12 and between the two plies. The elastic material 11 maintains a continuous stretching action on the cover and keeps the top surface 1 taut and wrinkle free. It also keeps the cotton side edging 3 pressed tightly against the side edges of the ironing board to which the cover is applied.

The invention provides an ironing board cover having an ironing surface or top made of asbestos to which thin fabric is cut on the bias, is secured. Elastic material is secured entirely about the free edge of the cotton material so as to maintain the ironing board cover in taut position over the ironing board. If desired, an ironing board pad 15 may be mounted on the top surface of the ironing board 2, the top 1 of the ironing board cover lying against the upper surface of the pad 15.

Changes may be made in the form, construction and arrangement of the pads without departing from the spirit of the invention, or sacrificing any of its advantages, and the right is hereby reserved to make all such changes as fall fairly within the scope of the following claims.

This invention is hereby claimed as follows:

1. An ironing board cover having a top surface

made of asbestos woven fabric and of a size substantially equal to the size of an ironing board top to which the cover is to be applied, cotton fabric material stitched to the outer edges of the asbestos material and completely thereabout, said cotton material being cut on the bias so as to provide a predetermined amount of stretch in two directions, and elastic material secured to the outer free edge of said cotton material about the entire periphery thereof.

2. An ironing board cover having a top surface made of asbestos woven fabric and of a size substantially equal to the size of an ironing board top to which the cover is to be applied, cotton fabric material stitched to the outer edges of the asbestos material and completely thereabout, said cotton material being cut on the bias so as to provide a predetermined amount of stretch in two directions, elastic material secured to the outer free edge of said cotton material about the entire periphery thereof and binding tape secured to the cover around the juncture of the asbestos fabric and the cotton fabric.

3. An ironing board cover having a top surface made of asbestos woven fabric and of a size substantially equal to the size of an ironing board top to which the cover is to be applied, cotton fabric material stitched to the outer edges of the asbestos material and completely thereabout, said cotton material being cut on the bias so as to provide a predetermined amount of stretch in two directions, elastic material secured to the outer free edge of said cotton material about the entire periphery thereof, said elastic material being folded upon itself to provide a mouth into which the free edge of the cotton material is received.
